DETACHABLE HANDLE FOR PAPER BAGS

Hugh P. Botts, New York, N. Y., assignor of one-half to Lawrence G. Botts, New York, N. Y.

Application February 25, 1944, Serial No. 523,939

19 Claims. (Cl. 229—54)

1

This invention relates to handles adapted for use in connection with ordinary paper bags used by storekeepers as containers for numerous individual articles or packages. More particularly, the invention relates to a handle member having means for quickly coupling and uncoupling the same with a wall portion or portions of the bag, preferably adjacent the upper or open end thereof, and which may be further used as a means for joining opposed wall portions of a bag including envelope types of bags. The novel features of the invention will be best understood from the following description when taken together with the accompanying drawing, in which certain embodiments of the invention are disclosed, and in which the separate parts are designated by suitable reference characters in each of the views, and in which:

Fig. 1 is a perspective view of an envelope type of bag or container, showing one form of handle member which I employ.

Fig. 2 is a view similar to Fig. 1, showing another form of handle member as attached to opposed walls of an ordinary paper bag, the upper end portion only of the bag being shown.

Fig. 3 is a plan view of the upper edge portion of the paper bag, showing a duplex handle construction.

Fig. 4 is an enlarged detail view of one end portion of a handle member made according to my invention, with part of the construction shown in section; and

Fig. 5 is an enlarged sectional plan view taken, for example, on the line 5—5 of Fig. 2, showing only a part of the construction on an enlarged scale.

In recent years, many storekeepers and particularly the grocery merchants have resorted to the use of ordinary paper bags for assembling a number of articles for carrying and transportation by the customer. This method of procedure has saved considerable time which heretofore was devoted to the wrapping of packages by the use of plain sheets of paper and string or twine. However, convenient carrying of particularly the large bags of the kind under consideration has been a problem, and is extremely tiresome, particularly in that the bags must be carried in the arms, especially when the bags are full or substantially fully loaded.

It is the purpose of my invention to obviate these objectionable features in the present use of bags of the kind under consideration by simply providing the purchaser with one or more handle members of simple construction, by means of

2

which bags of the kind under consideration can be conveniently carried, and where a number of the bags may be more conveniently handled, as will be apparent.

5 While handle members of the general type and kind under consideration may be elaborately constructed, for purposes of illustrating one adaptation and use of my invention, I have shown it in a simple and economical form. The handle member comprises a cord like strand 10 of heavy kraft paper, that is to say, will be composed of a number of independent paper strands 11 which are twisted or spiralled in forming the heavy strand 10. One reason for this is to provide a stout 10 handle member which will not cut the hands, and yet will present a smooth and soft texture which will not in any way injure the hand, particularly when heavy articles are carried in a large paper bag.

20 Each end portion of the strand 10 will be sealed, as indicated at 12, in any desired manner by a cement or by putting a seal thereon which will prevent untwisting or unravelling of the strands 11, and further form a finished edge. Adjacent 25 each end of the strand 10, a pin or filler member 13 is arranged within the coils or windings 11, and this pin has an inwardly tapering end 14, inwardly being here used with respect to the end 12. The pin 13 produces on the strand 10 an enlarged 30 body portion 15, against which a coupling sleeve 16 is adapted to be pressed in the operation of securing the handle member to the bag, as later described.

35 The sleeve 16 has a tapered bore 17, the outer end of which is rounded, as seen at 18, to provide free entrance of the body 15 into the bore 17. The outer end of the sleeve 16 is preferably beaded, as indicated at 19, to reinforce the sleeve, and further to form a grip thereon which will facilitate 40 moving the sleeve into the wedged or gripping position. It will be understood that the end 20 of the bore 17 is greater in diameter than the outside diameter of the inner end of the enlargement 15, whereas the end 21 is of a diameter to freely 45 clear the normal diameter of the strand 10. One side of the sleeve 16 has a slot 22 extending through the full length thereof, as will clearly appear in Fig. 4 of the drawing, and the outer end of the slot has a wide or flared entrance throat 50 23, which will facilitate free passage of the wall of a bag or other support therethrough.

The sleeve or wedge member 16 may be composed of any desired material, and will preferably have a slight spring action, so that the jaw por-

tions 24 at opposite sides of the slot 22 will yield laterally.

Probably the most common use of the invention will be in the construction of a handle member such as shown in Fig. 2 of the drawing, wherein the strand 18 includes one of the sleeves 16 at each end thereof. A device of this kind will have many uses for supporting and carrying articles of various kinds and classes, but for illustrative purposes the bag use of the handle member is here specifically dealt with. At 25 is shown the upper edge portion of a common bag of the type conventionally used by storekeepers for the purposes heretofore stated. At 26 is shown opposed wall portions of the bag. In coupling the handle member with the wall portions 26 of the bag, the enlarged portion 15 at the end of the handle member is arranged on one surface of one of the walls 26, preferably adjacent the upper edge of the wall, and the wall 26 is folded around the portion 15 to form a loop, as indicated at 27 in Fig. 5 of the drawing. The sleeve 16 is then moved downwardly over the strand 18, and the portions 28 extending from the loop 27 are passed through the slot 22 in the sleeve, and the sleeve is moved downwardly to firmly clamp itself upon the looped portion 27 of the bag and the enlarged portion 15 of the strand. This securely couples one end portion of the handle member with one side wall of the bag, then the other end of the handle member is similarly coupled with the other side wall of the bag, thus producing a result substantially similar to that shown in Fig. 2 of the drawing. To detach the handle member, all that is necessary is to slide the sleeve 16 inwardly onto the strand into a position substantially similar to that shown in full lines in Fig. 4 of the drawing, at which time, the bag or the wall portion 26 thereof can be freely removed.

It is the intent and purpose that after purchasing or otherwise acquiring a number of the handle members, which may be compactly folded into a small package or placed in a pocketbook or pocket, a purchaser can use and re-use the handle members until they become worn or otherwise rendered useless for the intended purpose. On the other hand, these handle members may be distributed as advertising mediums and placed on the bags by the merchant without any cost to the purchaser. From this standpoint, handle members may be pre-attached to the bags, particularly in that the handle members will not interfere in any material way with placement of articles in the bag.

In the above operation of moving the sleeve 16 into the wedged or coupled position, it will be apparent that movement of the tapered bore 17 over the tapered end portion of the pin 13 with the strands 11 thereon will produce a secure wedge jamming of the sleeve 16 in connection with the bag. On the other hand, the coupling with the bag is not localized, in that the engagement with the taper of the bag will be distributed more or less throughout the length of the coupling sleeve. This will avoid any tendency of weakening the structure of the bag, and will prevent tearing or rupture thereof.

It will be understood that the fundamental principles of the handle device may have many uses and adaptations. For example, a handle loop having a single sleeve may be employed, as illustrated in Fig. 1 of the drawing. In this figure, the handle member comprises a closed or permanent loop 29 having a projecting end 30 similar to one end of the strand, as shown in

10 Figs. 1, 4 and 5, and on the end 30, will be mounted a sleeve 31 similar to the sleeve 16.

15 In Fig. 1, an envelope type of bag or paper container is diagrammatically illustrated at 32. The folded flap end 33 of which controls the opened end of the container. Here the entire upper flap end of the container 32 can be coiled or folded around the end 30, and then the sleeve 31 moved into position to couple the handle member with the central portion of the flap end 33 of the container. This type of construction can be practically used in the many types and kinds of small envelope type of bags and containers used by dry-goods and other merchants for the packaging of small and light articles.

20 Where the bag does not include the flap 33, the open end of the bag may simply have opposed walls folded upon themselves to seal the open end of the bag, after which the handle member can be attached. This feature would also apply to the heavier types of bags, it being understood that the opposed wall portions 26 could be brought together, and the handle member ends coupled with both walls 26 by positioning the handle members adjacent end walls 34. At this time, it will be apparent that the slots 22 in the sleeves may be of sufficient width to compensate for the different uses.

25 In Fig. 3 of the drawing is shown another modification which comprises using two handle units 35 and 36, both of which will be of the same general structure as the single handle unit shown in Fig. 2 of the drawing. The two units 35 and 36 will be joined together by a strap handle portion 37, which may simply comprise a wide strip of suitable material having curled or other ends 38 enveloping the strand of the handle units 35 and 36, and if desired, may be fixedly secured to the central portions thereof.

30 The coupling sleeves 16-a, at the end of each handle unit 35 and 36 is adapted to be coupled with opposed side walls 39 of a paper bag adjacent the end walls 40 thereof, or in other words, adjacent the folded corner portions 41 of the bag. This type of dual or duplex handle construction would only be essential with the larger types of bags, and where extremely heavy articles are supported in the bag. The duplex handle structure will more equally distribute the strain 35 of the bag in carrying the contents, and further, a still larger hand grip portion will be provided in the handle member 37.

35 The twisting or spiralling of the several strands 11 forming the body portion of the handle member have a normal springing tendency to close one upon the other. However, by twisting the strand, the coils or windings will open sufficiently to facilitate insertion of the pins 13, after which the normal closing tendency will serve to grip the pin 13, and support it in proper position. By reason of the fact, that the position of the pins in the end portions of the handle member may be changed from time to time when it might be advantageous to increase or decrease the loop of the handle member, it will also be apparent that while in Figs. 2, 3 and 5 the sleeves are arranged upon the outer surfaces of the bags with the cord or strand ends arranged upon inner surfaces thereof, this position may be reversed. However, the position illustrated in Figs. 2, 3 and 5 is generally speaking probably the best, in that it maintains a free axis to the entire interior of the bag structure, particularly when carried in the fully opened position.

40 From a standpoint of a shiftability of the pins

13, it will be apparent that these pins may be shifted anywhere along a strand like body to form of a portion of the strand body and between the spaced wedge sleeves thereon, a handle member, the size of the handle member or loop being governed by the spacing of the pins one from the other on the cord like strand of the handle member. It will also be apparent that the invention comprises generally the arrangement of one or two coupling sleeves on a handle forming strand, with means at spaced intervals on the strand to wedge an article between said means and the sleeve or sleeves when moved into engagement with said means.

It will be apparent that the illustrations in the accompanying drawing with respect to the structure of the enlarged portions of the handle member are illustrative of one adaptation and use of the invention. It will be apparent that the principle of the formation of handle members as taught by these illustrations resolve in the provision of means forming an enlarged portion in the bag or other article in connection with which the handle is to be attached, and in the provision of a sleeve slidably engaging and preferably having the tapered wedge like coupling with the enlargement to provide a secure coupling with the article and then to extend from this coupling a single handle member or to use two of such couplings with a handle member extending therebetween.

Having fully described my invention, what I claim as new, and desire to secure by Letters Patent is:

1. The combination with a paper bag of the class described, of a handle member for detachable coupling with said bag, said handle member comprising a strand, enlarged portions at spaced intervals on the strand, a pair of sleeves mounted on the strand inwardly of said enlarged portions, said sleeves having slots longitudinally of the wall thereof, and the wall portions of a paper bag being adapted to be wrapped around enlarged portions of said strand and secured thereto by wedge engagement of the sleeves with that portion of the walls of the bag arranged on said enlarged portions.

2. A handle member of the class described, said handle member comprising a strand body, a longitudinally split sleeve slidably movable on said body, an enlarged portion on the strand checking movement of the sleeve in one direction thereon, and means providing a wedge like engagement between the sleeve and said enlarged portion to securely clamp and hold a support arranged therebetween.

3. A handle member of the class described, said handle member comprising a strand body, a longitudinally split sleeve slidably movable on said body, an enlarged portion on the strand checking movement of the sleeve in one direction thereon, means providing a wedge like engagement between the sleeve and said enlarged portion to securely clamp and hold a support arranged therebetween, said strand comprising a coiled multi-strand body, and the enlarged portion comprising a pin supported within the coils of said strand.

4. A handle member of the class described, said handle member comprising a strand body, a longitudinally split sleeve slidably movable on said body, an enlarged portion on the strand checking movement of the sleeve in one direction thereon, means providing a wedge like engagement between the sleeve and said enlarged por-

tion to securely clamp and hold a support arranged therebetween, said strand comprising a coiled multi-strand body, the enlarged portion comprising a pin supported within the coils of said strand, and one end of said pin being tapered.

5. An article of manufacture of the class described, comprising an elongated rope like member composed of a plurality of twisted strands, means disposed within said strands at one section of the member to expand the strands to form an enlarged portion on the member, and a longitudinally split sleeve slidably movable on said member and having a wedge like engagement with the enlarged portion thereof.

6. An article of manufacture of the class described, comprising an elongated rope like member composed of a plurality of twisted strands, means disposed within said strands at one section of the member to expand the strands to form an enlarged portion on the member, a longitudinally split sleeve slidably movable on said member and having a wedge like engagement with the enlarged portion thereof, and the strands of said member being composed of twisted paper.

7. An article of manufacture of the class described, comprising an elongated rope like member composed of a plurality of twisted strands, means disposed within said strands at one section of the member to expand the strands to form an enlarged portion on the member, a longitudinally split sleeve slidably movable on said member and having a wedge like engagement with the enlarged portion thereof, the strands of said member being composed of twisted paper, and said means comprising an elongated pin tapered in the direction of the sleeve disposed on said member.

8. An article of manufacture of the class described, comprising an elongated rope like member composed of a plurality of twisted strands, means disposed within said strands at one section of the member to expand the strands to form an enlarged portion on the member, a longitudinally split sleeve slidably movable on said member and having a wedge like engagement with the enlarged portion thereof, the strands of said member being composed of twisted paper, said means comprising an elongated pin tapered in the direction of the sleeve disposed on said member, said sleeve having a tapered bore, and the bore being flared outwardly in the direction of the tapered end of said pin.

9. An article of manufacture of the class described, comprising an elongated rope like member composed of a plurality of twisted strands, means disposed within said strands at one section of the member to expand the strands to form an enlarged portion on the member, a longitudinally split sleeve slidably movable on said member and having a wedge like engagement with the enlarged portion thereof, said enlarged portion being disposed at one end of said member, and a hand grip portion at the other end of said member.

10. A handle device for quick attachment and detachment with respect to a support, said device comprising an elongated member, means forming enlarged portions at the ends of said member, longitudinally split sleeves slidably movable on said member inwardly of said enlarged ends, and means forming a wedge like grip between the sleeves and said enlarged ends in securely gripping supports therebetween.

11. A handle device for quick attachment and detachment with respect to a support, said device comprising an elongated member, means forming enlarged portions at the ends of said member, longitudinally split sleeves slidably movable on said member inwardly of said enlarged ends, means forming a wedge like grip between the sleeves and said enlarged end in securely gripping supports therebetween, another handle device similar to the first named devices, and hand gripping means joining the members of said devices intermediate the sleeves on each member.

12. A handle device of the class described, comprising an elongated body of soft pliable material, means at spaced intervals on said body forming 15 inwardly tapered enlargements, a pair of longitudinally split sleeves on said body intermediate said tapered enlargements, and said sleeves having tapered bores flared in the direction of the tapered enlargements on said body and adapted to 20 wedgeably engage said enlarged tapered portions.

13. A handle device of the class described, comprising an elongated body of soft pliable material, means at spaced intervals on said body forming 25 inwardly tapered enlargements, a pair of longitudinally split sleeves on said body intermediate said tapered enlargements, said sleeves having tapered bores flared in the direction of the tapered enlargements on said body and adapted to 30 wedgeably engage said enlarged tapered portions, said body being formed of a plurality of twisted strands, and means sealing the strands beyond said enlarged portions.

14. The herein described means of forming a 35 handle portion of an elongated paper rope body, which comprises forming the body of a plurality of twisted paper strands, arranging pin like members within the strands at spaced intervals on said body to form at said intervals on the body 40 enlarged portions, arranging longitudinally split sleeves on the body intermediate the enlarged portions, and said enlarged portions in combination with said sleeves providing means for wedgeably securing the sleeves on said body at 45 said enlarged portions.

15. The herein described means of forming a 50 handle portion of an elongated paper rope body, which comprises forming the body of a plurality of twisted paper strands, arranging pin like members within the strands at spaced intervals on said body to form at said intervals on the body enlarged portions, arranging longitudinally split sleeves on the body intermediate the enlarged

portions, said enlarged portions in combination with said sleeves providing means for wedgeably securing the sleeves on said body at said enlarged portions, and means outwardly of the pin like members for sealing the strands of said body against unravelling.

16. In a handle structure for articles of the class described, a handle member, means forming an enlarged body portion on said member over which an article is adapted to be arranged, and a sleeve having a tapered bore slidably engaging the enlarged body portion and the article thereon in securing said handle member and sleeve to the article.

17. The herein described means for forming handles on articles of the class described, which comprises arranging members on spaced portions of an elongated handle, of an article, with the article extending around and at least partially enveloping said members, and moving split coupling sleeves over said spaced portions of the article in securing said members, sleeves and handle to said article.

18. A handle for bags of the class described, comprising a cord like handle part, a pin member arranged within a portion of said part to enlarge said portion, said enlarged portion of the handle part being adapted to engage a portion of a bag to be supported by said part, and a split sleeve slidably engaging that part of the bag having the enlarged portion of the handle part thereon in securely coupling the handle part with said bag.

19. A handle for bags of the class described, comprising a cord like handle part, a pin member arranged within a portion of said part to enlarge said portion, said enlarged portion of the handle part being adapted to engage a portion of a bag to be supported by said part, a split sleeve slidably engaging that part of the bag having the enlarged portion of the handle part thereon in securely coupling the handle part with said bag, and said pin member being tapered to taper said enlarged portion.
